UNITED STATES PATENT OFFICE.

SAMUEL J. DUNKLEY, OF KALAMAZOO, MICHIGAN, ASSIGNOR TO DUNKLEY COMPANY, OF KALAMAZOO, MICHIGAN, A CORPORATION OF MICHIGAN.

PITTING-KNIFE FOR PITTING PEACHES OR SIMILAR FRUITS.

1,370,099.

Specification of Letters Patent.

Patented Mar. 1, 1921.

Application filed January 11, 1917, Serial No. 141,888. Renewed May 31, 1919. Serial No. 301,118.

To all whom it may concern:

Be it known that I, SAMUEL J. DUNKLEY, a citizen of the United States, residing at Kalamazoo, county of Kalamazoo, State of Michigan, have invented certain new and useful Improvements in Pitting-Knives for Pitting Peaches or Similar Fruits, of which the following is a specification.

This invention relates to improvements 10 in pitting knives for pitting peaches or similar fruits or for the coring of fruit or the cutting of fruits or vegetables for various purposes.

The objects of the invention are, to provide 15 a knife structure that may be power driven so that the speed of operation is greatly enhanced.

A specific object is, to provide a structure 20 with means for oscillation or vibration of the cutting blade to facilitate the cutting qualities.

Further objects, and objects relating to 25 details and economies of construction and operation will definitely appear from the detailed description to follow.

I accomplish the objects of my invention 30 by the devices and means described in the following specification. The invention is clearly defined and pointed out in the claims.

A structure which is a preferred embodiment of my invention is illustrated in the accompanying drawing forming a part of this specification, in which:

35 Figure I is a perspective view somewhat reduced in size of my improved pitting and cutting knife.

Fig. II is a detail longitudinal section, somewhat enlarged, the driving shaft and the wrist pin being shown in full lines.

40 Fig. III is an enlarged detail transverse sectional view on line 3—3 of Fig. II, showing details of construction of the oscillating or vibrating means.

45 Fig. IV is an enlarged detail transverse sectional view on line 4—4 of Figs. I and II, through the knives showing the beveling of same.

Fig. V is an enlarged detail sectional view 50 on line 5—5 of Fig. II showing the disposition of the wrist pin within the oscillating couplings of the knife head.

In the drawings, the sectional views are taken looking in the direction of the little 55 arrows at the ends of the section lines, and

similar numerals of reference refer to similar parts throughout the several views.

Considering the numbered parts of the drawing, 1 is the handle of convenient dimensions, provided with a flange 1' which 60 carries the oscillating knife head 2 on a pin 3, which is carried by a pair of fingers 3'. The blade 4 has a cutting part in the form of an arc of a circle, the radial center of which is the axis of oscillation of the head 65 2. The blade 4 is of sheet metal preferably beveled on the inner side and serrated at 4' and retained in place in suitable seats in the head 2 by means of locking screws 5, 5, one at each end. The revoluble shaft 6, which 70 may be revolved by a flexible shaft or any suitable means, as a direct connected electric motor, is supported in a journal block 7 in the handle 1 and extends through journal bearings 6' in the head of the handle and is 75 provided with a head 8 carrying a wrist pin 9. A pin 10 is supported in a partial bearing 10' in the head 2, the axis of which is parallel to the axis of oscillation of said head. Pin 10 contains the longitudinal slot 80 11 in which the wrist pin 9 plays, and on its rotation oscillates the head 2 thereby oscillating the blade 4 in a circular path causing the same to cut very rapidly and with substantially no resistance. 85

The blade in the hand of the operator passes very readily through the pulp of a clingstone peach and makes a clean cut. It will cut any fruit or vegetable with which it may be brought in contact. This is of the 90 highest advantage and facilitates the removal of pits from clingstone peaches, also cutting cores from pears, the eyes from pineapples, and doing any other work of a similar character. 95

The blade can be rocked by the hand to cut out the half of a round pit or can be moved along to cut out a long one or to cut out a long core. Peaches or other fruit are cut or sawed in half preliminary to using 100 my improved knife.

I am aware that there are a great variety of ways by which a blade of this kind may be oscillated, in fact, different mechanisms may be used, and it would be possible to 105 oscillate the knife without the intervention of a revolving shaft. I, however, have shown a specific construction which is preferred by me for the uses indicated and I desire to claim it specifically and I also de- 110

sire to claim the invention broadly as indicated and pointed out in the appended claims.

Having thus described my invention, what I claim as new and desire to secure by Letters Patent, is:

1. In a pitting knife, the combination of a suitable handle with a flange thereon, an oscillating knife head on a pivot transverse thereto, a pair of fingers on said handle for supporting said pivot, a driving shaft disposed in bearings in said handle with a head at its outer end between said fingers, a wrist pin on said head, a pin in said knife head parallel to its said axis of oscillation in a partial journal bearing containing a longitudinal slot with which the said wrist pin co-operates, and disposed between said fingers and retained thereby, a serrated blade beveled on its inner side constituting an arc of a circle, the center of which is in the said pivot pin, and means for securing the said blade detachably to the said head, coacting for the purpose specified.

2. In a pitting knife, the combination with a suitable handle, of an oscillating knife head suitably pivoted thereon, a driving shaft disposed in bearings in said handle, connections therefrom to oscillate the said head, a blade forming an arc of a circle carried by said head, the center of which circle is the center of oscillation of said head, coacting as specified.

3. In a pitting knife, the combination of a suitable handle, a serrated blade carried by said handle, the cutting edge of which is in the form of an arc of a circle and beveled on its inner side, and means connected to oscillate or vibrate the said blade, as specified.

4. In a pitting knife, the combination of a suitable handle, a blade carried by said handle, the cutting edge of which is in the form of an arc of a circle and beveled on its inner side, and means connected to oscillate or vibrate the said blade, as specified.

5. In a pitting knife, the combination of a suitable handle, a serrated blade carried by said handle, the cutting edge of which is in the form of an arc of a circle, and means connected to oscillate or vibrate the said blade, as specified.

6. A pitting knife comprising a thin blade bent in substantially an arc of a circle, a handle pivotally secured thereto at the center of said arc, and means for oscillating said blade about the said center, the edges of said blade being unobstructed.

7. In a pitting knife, the combination of

a suitable handle, a curved blade, the cutting edge of which is in the curved plane of the blade, carried by said handle, and means connected to oscillate or vibrate the said blade in the direction of its length, as specified.

8. In a pitting knife, the combination of a suitable handle with a flange thereon, an oscillating knife head on a pivot transverse thereto, a pair of fingers on said handle for supporting said pivot, a driving shaft disposed in bearings in said handle with a head at its outer end between said fingers, a wrist pin on said head, a pin in said knife head parallel to its said axis of oscillation in a partial journal bearing containing a longitudinal slot with which the said wrist pin co-operates, and disposed between said fingers and retained thereby, and a blade beveled on its inner side constituting an arc of a circle, the center of which is in the said pivot pin, coacting for the purpose specified.

9. In a pitting knife, the combination of a suitable handle with a flange thereon, an oscillating knife head on a pivot transverse thereto, a pair of fingers on said handle for supporting said pivot, a driving shaft disposed in bearings in said handle with a head at its outer end between said fingers, a wrist pin on said head, a pin in said knife head parallel to its said axis of oscillation in a partial journal bearing containing a longitudinal slot with which the said wrist pin co-operates, and disposed between said fingers and retained thereby, and a serrated blade constituting an arc of a circle, the center of which is in the said pivot pin, coacting for the purpose specified.

10. In a pitting knife, the combination of a suitable handle with a flange thereon, an oscillating knife head on a pivot transverse thereto, a driving shaft disposed in bearings in said handle with a head at its outer end between said fingers, a wrist pin on said head, a pin in said knife head parallel to its said axis of oscillation in a partial journal bearing containing a longitudinal slot with which the said wrist pin co-operates, and disposed between said fingers and retained thereby, and a blade constituting an arc of a circle, the center of which is in the said pivot pin, coacting for the purpose specified.

In witness whereof I have hereunto set my hand and seal in the presence of two witnesses.
